UNITED STATES PATENT OFFICE.

LEOPOLD HAUSER, OF NEW YORK, N. Y., ASSIGNOR OF ONE-HALF TO SIMON WEIL, OF NEW YORK, N. Y.

BELT PIN OR BUCKLE.

959,340.

Specification of Letters Patent.

Patented May 24, 1910.

Application filed April 17, 1908. Serial No. 427,642.

To all whom it may concern:

Be it known that I, LEOPOLD HAUSER, a citizen of the United States, and a resident of the borough of Manhattan of the city of New York, in the county and State of New York, have invented certain new and useful Improvements in Belt Pins or Buckles, of which the following is a specification, reference being had to the accompanying drawings, forming a part hereof.

The invention has for its object the provision of an ornamental initial plate which may be embodied in a belt pin or buckle and in many other devices, and in which provision is made for the insertion and adjustment of initial letters whereby it is possible to provide in any plate any particular set of initials desired.

The improved device has been constructed with particular reference to making it easy and convenient to insert and adjust the letters within the plate and to retaining the letters securely therein after the parts of the device have been assembled. The invention will be more fully described hereinafter with reference to the accompanying drawings in which,

Figure 1 is a plan view of a buckle embodying the invention, Fig. 2 is a similar view with the front portion of the frame removed. Fig. 3 is a sectional view, the plane of section being indicated by the line 3—3 in Fig. 1. Fig. 4 is a plan view of one of the letters employed therein, and, Fig. 5 is a detail view showing the two parts of the frame hinged together.

As illustrated, the improved buckle has a frame portion consisting preferably of two parts *a* and *b* in which the letters or plates *c* are arranged and secured. The part *a* is provided on one or more of its bars with means for positioning the letters, such as teeth *d*, and the part *b*, which may be united to the part *a* in any suitable manner, constitutes the means for retaining the letters in position and in the present case forms the ornamental front piece of the buckle. The teeth *d* are preferably formed integral with the part *a*, the latter being stamped out of a suitable piece of metal so as to have a central opening into which the teeth *d* project. The teeth *d* are then subsequently bent out of the plane of this back frame *a* and preferably at substantially right angles therewith (Fig. 3) so that when the front part

of the frame *b* is in position, the upper ends of the teeth rest flatly against it and form with it well defined slots in which the letters *c* are retained through their projecting ends *e*. These projecting ends *e* are preferably 60 T-shaped so that when the letters are in position within the frame, their T-shaped ends will rest flatly between the parts *a* and *b* and will prevent the letters from twisting.

The general shape of the buckle may be 65 varied at pleasure, but it is preferably curved as shown in Fig. 3 so as to conform more accurately to the body of the wearer. With such a shape, the back frame *a* may be secured to the front frame *b* by springing 70 the back frame into the front frame, as will be easily understood, small clips *f* or similar fastening pieces being provided at the ends of the frame *b* to maintain the two parts of the frame in engagement. As 75 shown in Fig. 5 a hinge *g* may be provided between the two parts of the frame at one end. Moreover, the back piece *a* may be provided as usual with a suitable belt attachment *m* and a fastening hook *n* as illustrated. 80

The improved buckle enables the initial letters to be assembled conveniently and expeditiously, for with the part *b* removed, the letters are first inserted in the desired 85 positions between the teeth *d* upon the back piece *a* and then the front piece *b* is snapped down upon them holding them in position. The insertion of the letters is made while the front end of the back piece is facing 90 the person who is inserting the letters so that as the letters are inserted they read in their proper order instead of in the reverse order as would be the case if the letters had to be inserted upon the rear side of the 95 front piece *b*. This is very important because it enables the person inserting the letters to tell how they are going to appear and therefore to tell whether he has them correctly inserted or not without having to 100 turn the buckle over to see them in their right order. Moreover, the teeth which are bent out of the plane of the back piece and meet the front piece together with the T-shaped extensions upon the top and bottom 105 of the letters, offer a very satisfactory means of maintaining the letters in their correct positions within the frame.

It is obvious that various departures, within the scope of the appended claim, may be 110

made from the construction shown and described herein without avoiding the spirit of the invention. For instance, the belt or buckle embodying the invention may be
5 made in any size or in any shape and it may be adapted to contain one letter or two or more initials or a sufficient number of letters to constitute a full name.

I claim as my invention:
10 The combination of a frame having teeth bent at right angles thereto, letters having

extensions at top and bottom to fit between the teeth, and means bearing upon the extensions as they lie between the teeth and the frame to retain the letters in position.

15

This specification signed and witnessed this 13th day of April, A. D. 1908.

LEOPOLD HAUSER.
